UNITED STATES PATENT OFFICE.

CHARLES FOSBY, OF RUTHERFORD, NEW JERSEY.

PROPORTIONAL DIVIDERS.

SPECIFICATION forming part of Letters Patent No. 730,105, dated June 2, 1903.

Application filed September 5, 1902. Serial No. 122,203. (No model.)

To all whom it may concern:

Be it known that I, CHARLES FOSBY, a citizen of the United States, residing in Rutherford, in the county of Bergen and State of New Jersey, have invented a certain new and useful Improvement in Proportional Dividers, of which the following is a specification.

The invention relates to instruments for proportionally increasing or decreasing measurements in making enlarged or reduced copies, and is designed more especially for service in laying out the required pattern of cutter or knife to produce a molding of desired pattern.

15 The cutters of a molding-machine are secured to the plane faces of the cutter-head at points removed from the center of rotation, and as they are not radial to the latter the contour of the cutting edge of each knife requires to be somewhat different from the profile of the finished molding.

20 The object of my invention is to provide an easily-operated instrument by which the cutters to produce any desired pattern may be quickly and accurately laid out and by which the cutters may be properly adjusted on the cutter-head.

25 The invention consists in certain combinations and arrangements of parts by which the above objects are attained, to be hereinafter fully described.

30 The accompanying drawings form a part of this specification and show the invention as I have carried it out.

35 Figure 1 is a diagram showing the cutter-head of a molding-machine and illustrating the difference in contour of the knife and molding. Fig. 2 is a face or front view of the instrument. Fig. 3 is a corresponding view of the opposite face. Fig. 4 is a corresponding edge view, and Fig. 5 is a transverse section taken on the line 5-5 in Fig. 3.

40 Similar letters of reference indicate the same parts in all the figures where they appear.

45 In Fig. 1, A is the cutter-head of a molding-machine of any ordinary or approved type, and A' is one of the knives, secured thereto by bolts and nuts, as usual, the whole adapted to be revolved at the required speed by any suitable means (not represented) in the direction to act upon the face of the

wood strip, as will be understood. A⁴ is a dotted line drawn through the axis of the cutter-head and intersecting the base-line A³ at a right angle, and A² is a line in the plane of the cutting edge of the knife parallel with the line A⁴. At B is shown in full lines a pattern of a molding to be produced, erected on the base-line A³. A series of lines A⁵, drawn parallel with the base-line, pass through the several angles of the pattern and are extended to the axial line A⁴, whence they are projected in segments of circles from the axis of the cutter-head to the line A² and thence are again projected in straight lines A⁶ parallel with the base-line. The contour of the cutting edge of the knife may be laid out on these lines, as shown by the heavy dotted lines at A⁷. It will be observed by comparing this contour with the pattern B (again shown for convenience in comparison by the lighter dotted lines at B' within the lines A⁷) that the lines indicating width of the several members comprising the molding are unchanged, but that the lines indicating depth are considerably increased in length, and, further, that the difference is more marked or proportionately greater near the cutter-head because of the greater angle produced by the shorter radius.

55 My improved instrument is designed to correspondingly increase the vertical measurements of the pattern in laying out the knife and also to provide for the slight change in proportion due to the difference in radial distance, as pointed out above.

60 Referring to Figs. 2, 3, 4, and 5, in which the instrument is shown, C is the main member, preferably of thin metal, having two oppositely-extending fixed legs C' C², terminating in points C³ C⁴. D is a member of similar material pivoted to the member C at d near the root of the leg C' and having the leg D' extending approximately parallel with the leg C² and terminating in the point D³ adjacent to the point C⁴. A short oppositely-extending arm D² terminates in a boss or abutment D⁴, against which impinges the end of a screw M, passing through a threaded lug C⁵ on the leg C' and having a milled head M', by which it may be advanced or withdrawn. A third member E, pivotally connected to the member C at e near the root of

the leg C^2 , has a leg E' and point E^2 extending in the same direction as the leg C' and has also an arm E^3 extending across the leg D' and carrying a pin E^4 , having a lipped head E^5 , 5 by which the leg D' is engaged. On the opposite face of the member C is a cap or hollow casing F , containing a coiled spring F' , having an arm F^2 extending outwardly and engaging a pin E^6 on the leg E' and exerting 10 its force in the direction to close the instrument by drawing the leg E' toward its mate C' at one end and, through the engagement of the arm E^2 with the leg D' , also drawing the latter toward its mate C^2 at the opposite end of the instrument. The instrument 15 is opened and set by turning the screw M in the direction to force the abutment D^4 away from the lug C^5 , thus separating both pairs of legs. Any measurement taken by the 20 points $C^4 D^3$ will be proportionately increased at the points $C^3 E^2$ by reason of the greater movement of the leg E' , due to the difference in length of such leg and its arm E^3 , and also to the point of engagement of the latter with 25 the leg D' , as will be understood, and, so far as yet described, the ratio will be nearly constant. In order to induce the required lessening of the ratio as the measurements increase in depth in laying out the knife, the 30 slightly-curved incline D^5 is provided to receive the pin E^4 and cause the latter in its sliding engagement with the leg D' to descend the incline as the space between the legs C^2 and D' widens and to ascend the incline as 35 such space becomes less. By properly shaping the incline relatively to the position of the pivots d and e and other elements determining the proportions the instrument will compensate very exactly for the increasing 40 flatness of the curves described by those portions of the knife having increased radial length.

In using the instrument for the purpose described the pattern of the desired molding 45 is first laid out upon a predetermined base-line representing the bed of the molding-machine, with as many vertical ordinates and corresponding cross-lines as may be necessary or desired, and the width measurements 50 transferred without change to similar ordinates and lines on the knife pattern. These several depth measurements are then taken by the points $C^4 D^3$ and applied to the knife pattern by reversing the instrument and 55 pricking off the distances indicated by the points $C^3 E^2$. By joining the several points thus obtained the knife pattern is completed. The instrument also serves a useful function in exactly indicating the 60 projection the blades should have relatively to the cutter-head and to the base-line of the molding pattern in setting the knives.

Although I have described the invention as 65 designed for use in connection with molding-machines, it will be understood that it may serve for other purposes and may be modified

in the forms and proportions of its parts to conform to the requirements of such service.

I claim—

1. In proportional dividers, two pairs of 70 oppositely-extending legs pivotally connected and means for simultaneously adjusting both pairs of legs, the distance between the terminals of one pair being greater than that between the terminals of the other pair, in 75 combination with means for automatically varying the ratio between the said distances as the latter are increased or diminished.

2. A member C having two oppositely-extending fixed legs $C' C^2$, a member D pivotally mounted thereon having a leg D' extending approximately parallel with the leg C^2 to form a pair therewith, a member E pivotally mounted on said member C and having a leg E' extending approximately parallel with the 85 leg C' to form an opposite pair, and an arm E^3 engaging said leg D' , in combination with means for separating the legs of said pairs simultaneously and for drawing them together. 90

3. A member C having two oppositely-extending fixed legs $C' C^2$, a member D pivotally mounted thereon having a leg D' extending approximately parallel with the leg C^2 to form a pair therewith, a member E pivotally 95 mounted on said member C and having a leg E' extending approximately parallel with said leg C' to form an opposite pair, an incline D^5 on said leg D' , an arm E^3 on said member E having a pin E^4 engaging said incline, and 100 means for separating the legs of said pairs simultaneously and for drawing them together, all combined and arranged to serve substantially as herein specified.

4. The member C having the legs $C' C^2$, the 105 member D pivotally mounted thereon and having the leg D' and abutment D^4 , the member E pivotally mounted on said member C and having the leg E' and an arm E^2 engaging said leg D' , a lug C^5 on said leg C' , a screw 110 in said lug impinging against said abutment and serving to separate said legs, and a spring serving to draw said legs together, all combined substantially as herein specified.

5. A member C having two oppositely-extending fixed legs $C' C^2$, a member D pivotally mounted thereon having a leg D' extending approximately parallel with the leg C^2 to form a pair therewith, a member E pivotally 115 mounted on said member C and having a leg E' extending approximately parallel with said leg C' to form an opposite pair, an incline D^5 on said leg D' , an arm E^3 on said member E having a pin E^4 engaging said incline, an abutment D^4 on said member D , a screw M 120 carried on said fixed leg C' and impinging against said abutment, a spring F' and cap F therefor carried on said member C and engaged with said leg E' , said screw and spring serving as means for separating the legs of 125 said pairs simultaneously and for drawing them together, all combined and arranged to 130

serve substantially as and for the purposes set forth.

6. In proportional dividers, two pairs of oppositely-extending legs, means for fixedly, pivotally connecting the same and means for simultaneously adjusting both pairs of legs, the distance between the terminals of one pair being greater than that between the terminals of the other pair, combined with means for automatically varying the ratio between the said distances as the latter are increased or diminished.

7. In proportional dividers, a member having oppositely-extending fixed legs, oppositely-extending legs pivotally mounted thereon on fixed pivots, means on said member for simultaneously adjusting both of said pivoted legs, said legs being of different lengths, and means for automatically varying the ratio between the distances between the adjacent

terminals of the legs as said distances are increased or diminished.

8. In proportional dividers a member having oppositely-extending legs, a member pivotally mounted thereon and having a leg co-operating with one of the legs of the first-mentioned member, a member pivotally mounted on the first-mentioned member and having a leg co-operating with the other leg thereof, combined with means for automatically varying the proportions of the spaces between the terminals of each pair of legs, substantially as described.

In testimony that I claim the invention above set forth I affix my signature in presence of two witnesses.

CHARLES FOSBY.
